United States Patent Office

Des. 180,386
Patented June 4, 1957

180,386

ICE BUCKET

Ralph B. Billig, Westlake, and Manuel S. Ziskin,
Mayfield Heights, Ohio

Application May 28, 1956, Serial No. 41,686

Term of patent 14 years

(Cl. D58—17)

FIG. 3

5
5FIG. 4

FIG. 5

Fig. 1 is a perspective view of an ice bucket, showing our new design;

Fig. 2 is a cross-sectional view taken through the cover portion thereof on an enlarged scale.

Fig. 3 is a top plan view thereof with the handle in non-operating position;

Fig. 4 is a side elevational view thereof showing the cover removed from the bucket; and

Fig. 5 is a cross-sectional view thereof taken on the line 5-5 of Figure 2.

We claim:

The ornamental design for an ice bucket, as shown.
